UNITED STATES PATENT OFFICE.

IRA W. NONNEMAN, OF WARREN, OHIO, ASSIGNOR TO THE BORDEN COMPANY, OF
WARREN, OHIO, A CORPORATION OF OHIO.

DIESTOCK.

1,338,863.

Specification of Letters Patent.

Patented May 4, 1920.

Application filed September 16, 1918. Serial No. 254,232.

To all whom it may concern:

Be it known that I, IRA W. NONNEMAN, a citizen of the United States, residing at Warren, in the county of Trumbull and 5 State of Ohio, have invented a certain new and useful Improvement in Diestocks, of which the following is a full, clear, and exact description, reference being had to the accompanying drawings.

10 This invention relates to a simple and cheap die stock having means permitting the thread cutting chasers to properly recede from the pipe as the threading progresses. The object is to provide a very 15 simple structure by which the die stock may be readily guided on the pipe and the receding of the chasers effectively accomplished. To this end I provide a chaser carrying frame, a movable sleeve having a 20 tapered engagement with shoulders on the chasers and a device carried by the sleeve and adapted to engage the interior of the pipe being threaded and at once provide a guide for the die stock and an abutment 25 holding the sleeve against longitudinal progress, so that the chaser will be allowed to recede as the threading takes place.

An approved embodiment of my invention is illustrated in the drawings hereof 30 and is hereinafter more fully explained and the essential characteristics are summarized in the claims.

In the drawings, Figure 1 is an end or face view of the die stock; Fig. 2 is a side 35 elevation of such die stock; Fig. 3 is an elevation from the opposite direction from Fig. 1, being a section through the pipe being threaded; Fig. 4 is a longitudinal section through the die stock and pipe, on the 40 angular planes indicated by the line 4-4 on Fig. 3; Fig. 5 is a perspective view of one of the chasers employed.

As shown in Figs. 1 to 4, 10 indicates a 45 chaser carrying frame consisting of a flat ring-like portion 11, bosses 12 carried thereby and radially slotted to accommodate the chasers and a cylindrical extension 13. Secured to the face of the bosses are plates 15 and in the rectangular housings thus provided are the radial chasers 20. The frame is provided with integral diametrically opposed sockets 18 into which are screw 50 threaded the usual operating handles 30.

40 indicates a cup-like bushing having a

portion 42, with a cylindrical exterior occupying the bore 16 of the chaser carrying frame. The cylindrical member 42 is internally tapered corresponding to the taper of the thread to be cut. The chasers 20 extend through notches 44 in this controlling sleeve. Each chaser has in its side a notch 21 with an inclined inner wall 22 of the same taper as the sleeve 42. The body of this sleeve adjacent to the notch occupies the grooves 21 of the different chasers. 55

It results from the construction described that the sleeve 42 forms an abutment member limiting the outward movement of the chasers, while if this sleeve is drawn longitudinally out of the chaser carrying frame, 60 it will permit the chasers to move outward radially, thus providing for the tapered thread desired. To effect such movement of the sleeve automatically, I provide the abutment member 50. This is a cup-like 70 member swiveled to the member 40 by means of an axial cap-screw 51 extending through the member 40 and into the member 50. The member 50 has a cylindrical extension 52, a portion of which is of reduced diameter. This reduced portion is adapted to fit with reasonable snugness the interior of a pipe being threaded, as the pipe A in Figs. 3 and 4, and thereby guide the die stock. The shoulder 53 where the 80 reduced portion of the sleeve terminates is adapted to form an abutment against the end of the pipe A and stop the abutment bushing 40. 85

In the use of my die stock, the sleeve 52 90 is inserted within the end of the pipe A to be threaded, and the frame and chasers are rotated. The sleeve 52 serves to guide the die stock and properly present the chasers to the pipe. After the threading is continued to the point where the chasers should recede, the shoulder 53 abuts the end of the pipe A as shown in Fig. 4. Then as the rotation of the die stock continues, the abutment bushing 40 continues to rotate about 100 the screw 51 but can not travel with the chaser carrying frame and therefore the latter draws off of this abutment sleeve. This releases the chasers so that they move relatively outward as allowed by the taper of 105 the sleeve 42.

It will be seen that my die stock is very simple in construction but readily accom-

plishes the combined result of properly guiding the die stock and insuring the proper withdrawal of the chasers.

Having thus described my invention, 5 what I claim is:

1. In a die stock, the combination of a rotary frame, a cup-shaped bushing having its wall occupying the interior of the frame, said wall being internally tapered, chasers 10 carried by the frame engaged by said tapered portion, and a member having a cylindrical sleeve portion adapted to engage the interior of a pipe and a larger portion adapted to abut the end of the pipe and a 15 head adapted to stand adjacent to the head of said cup-shaped bushing, and means for connecting the two heads by a swivel at the axis of the die stock.
2. In a die stock, the combination of a 20 frame having a bore, chasers carried by the frame extending into the bore, a bushing occupying the frame having longitudinal slots extending from one end, said bushing having a tapered interior, and said chasers 25 occupying the slots and tapered shoulders engaged by tapered material of the bushing at the corresponding edge of the slots, and means for causing said bushing to shift in the chaser frame as the threading progresses.
3. In a die stock, the combination of a 30 frame having a bore, chasers carried by the frame extending into the bore, a bushing occupying the frame having openings 35 through which the chasers extend, said bushing having a tapered interior, and said chasers having correspondingly tapered shoulders engaged by tapered material of the bushing, and means for causing said 40 bushing to shift in the chaser frame as the threading progresses.
4. In a die stock, the combination of a frame, having a cylindrical extension and a

continuous cylindrical bore through the frame and extension, a sleeve occupying said bore and having a tapered interior, there being notches through the sleeve, and chasers carried by the frame and extending through said notches and having tapered shoulders adapted to be engaged by the sleeve. 45

5. In a die stock, the combination of a rotary frame, having radial chaser housings and having an internal bore, adapted to surround a pipe at some distance from it, radial chasers occupying said housings, a sleeve 50 occupying such bore having openings for the passage of the chasers, and having tapered inner edges adapted to engage tapered shoulders on the chasers, said sleeve having a portion extending across the end of the pipe, and a member axially swiveled to said 55 extending portion of the sleeve and having a guiding portion adapted to engage the interior of the pipe.

6. In a die stock, the combination of a 60 rotary frame having radial chaser housings and having an internal bore adapted to surround a pipe at some distance from it, radial chasers occupying said housings and adapted at their inner ends to engage the pipe, a 65 sleeve occupying such bore and having openings for the passage of the chasers and having tapered inner edges adapted to engage 70 tapered shoulders on the chasers, said sleeve having a portion extending across the end of the pipe, and a member having a cylindrical sleeve portion adapted to engage the interior of a pipe and a larger portion 75 adapted to abut the end of the pipe and a head adapted to stand adjacent to the head 80 of said sleeve, and means for connecting the two heads by a swivel at the axis of the die stock.

In testimony whereof I hereunto affix my signature.

IRA W. NONNEMAN.
